UNITED STATES PATENT OFFICE.

HARRY JOHANSEN, OF CHICAGO, ILLINOIS, ASSIGNOR TO SULLIVAN MACHINERY COMPANY, A CORPORATION OF MASSACHUSETTS.

CLAMPING MECHANISM.

1,355,082.

Specification of Letters Patent.

Patented Oct. 5, 1920.

Application filed November 28, 1917. Serial No. 204,457.

To all whom it may concern:

Be it known that I, HARRY JOHANSEN, a citizen of the United States, residing at Chicago, in the county of Cook and State of Illinois, have invented certain new and useful Improvements in Clamping Mechanisms, of which the following is a full, clear, and exact specification.

My invention relates to clamping mechanisms.

It has for its object to provide improved work clamping means whereby the friction is decreased and the power required to operate the mechanism is thus materially reduced. A more specific object of my invention is to provide improved work clamping mechanism wherein through the use of improved means for absorbing the thrust of the clamp operating mechanism, the above ends are attained. These and other objects and advantages of my improvement will, however, hereinafter more fully appear.

In the accompanying drawings, I have shown for purposes of illustration one embodiment which my invention may assume in practice.

In these drawings,—

Figure 1 is a side elevation of a standard type of forging machine equipped with my improvement, certain parts being broken away to show the clamp operating mechanism.

Fig. 2 is a detail sectional view taken substantially on line 2—2 of Fig. 1, showing the clamp and clamp operating mechanism.

Fig. 3 is a fragmentary view of the operating mechanism in a different position.

In this illustrative construction, I have shown in simplified form a forging machine adapted to the manufacture and sharpening of drill bits, which is of a type now manufactured commercially. As illustrated, this machine comprises a frame or base 1 carrying thereon a suitable stationary clamping die 2 and a vertically reciprocable clamping die 3, the latter being carried by and between spaced parallel columns 4 reciprocable in the frame to move the upper clamping die 3 to and from its clamping position. As in the commercial construction mentioned, these columns are also connected at their lower ends to a crosshead 5 movable in suitable guideways in the frame and connected through a toggle link 6 with a reciprocating

member or block 7, in turn connected to a piston 8 movable in a suitable cylinder 9 under the control of valve mechanism 10 controllable by a valve controlling lever 11. As usual, the base 1 also carries a horizontally disposed percussive motor 12 adapted to operate a dolly 13 to act upon the work clamped between the clamping dies, this motor also being controlled by the controlling lever 11 through the valve mechanism 10. It will also be observed that, as in the usual commercial construction, another percussive motor 14 is provided on a suitable vertical standard 15 to reciprocate a movable swaging die 16 relative to a stationary swaging die 17 carried on the frame 1, the motor 14 being controlled through suitable controlling mechanism including a foot-lever 18.

In my improvement, it will be observed that I have provided an overhanging link 19 pivotally connected to the toggle link 6 by a pin 20 at a point intermediate the ends of the link 6 and also suitably pivotally connected at 21 to the frame 1 at a higher point substantially in horizontal alinement with the upper pivot of the toggle link 6 when the latter is in its clamping position shown in Fig. 1, or in its non-clamping position shown in Fig. 3. As shown, this link 19 is adapted to be received in a suitable cut-away portion or recess 22 in one side of the link 6, although obviously this construction may be modified. In a preferred form, the pivot pin 20 of the link 19 is also located slightly below the transverse center line of the link 6 and at a point slightly at one side of the longitudinal center line thereof, the pivot of the same preferably being offset and disposed relative to the link 6 substantially as shown in Fig. 1.

In the operation of my improved construction, it will be observed that the toggle mechanism will be controlled in substantially the same manner in which it now operates in the type of machine hereinbefore referred to, the same being set, under the control of the valve mechanism 10 and 11, when the piston 8 is reciprocated toward the right in the cylinder 9, and broken when the piston is reciprocated in the opposite direction. More specifically, it will be observed that with the parts in the clamping position shown in Fig. 1, the lower end of the link 19

is freely movable upward with the link 6 to the non-clamping position thereof shown in Fig. 3, and that when the operation of the parts is reversed the link 19 transmits the 5 thrust to the frame 1 and simultaneously swings downward about its pivot to the clamping position shown.

In my improved construction wherein the link 19 moves about a fixed pivot on the 10 frame 1, it will be observed that due to the action of the link 19 the thrust of the clamp operating mechanism is taken by the frame 1 in such a manner as materially to reduce the friction of the parts and enable the same 15 to be operated with far greater facility. In fact, it has been demonstrated that a machine equipped with my improvement may be operated by a nine-inch piston and produce the same results as those heretofore 20 only obtainable with the use of a twelve-inch piston, thus clearly indicating that the efficiency of the mechanism has been materially increased.

While I have in this application specifically described one embodiment which my invention may assume in practice, it will be understood that this form of the same is used for purposes of illustration and that the invention may obviously be modified and 25 embodied in various other forms without de-

parting from its spirit or the scope of the appended claims.

What I claim as new and desire to secure by Letters Patent is:

1. In combination with a movable clamp member, a member reciprocable in a straight line, a link pivoted at one end thereto, said link being pivoted at its opposite end to the movable clamp member, and a second link pivoted to said first mentioned link at a 35 point between the ends thereof and outside a line connecting the first mentioned pivot points, said second mentioned link having also a fixed pivotal connection.

2. In combination, a frame, clamping 40 mechanism thereon including a reciprocable member, a second member reciprocable at right angles to said first mentioned member, a link pivoted to each of said members, and a second link pivoted at one end to said first 45 mentioned link and between the ends thereof and outside a line connecting the pivots, said second mentioned link having its other end pivoted to said frame, the upper pivot points of said links being on opposite sides of a 50 vertical line passing through the pivot point of the lower end of said first mentioned link when the parts are in clamping position.

In testimony whereof I affix my signature.
HARRY JOHANSEN.
